UNITED STATES PATENT OFFICE.

FREDERICK W. KOEHLER, OF CHICAGO, ILLINOIS.

COMBINED SHELF AND TOWEL-RACK.

1,090,724.

Specification of Letters Patent. Patented Mar. 17, 1914.

Application filed March 18, 1913. Serial No. 755,250.

To all whom it may concern:

Be it known that I, FREDERICK W. KOEHLER, a citizen of the United States, residing at Chicago, in the county of Cook and State 5 of Illinois, have invented new and useful Improvements in Combined Shelves and Towel-Racks, of which the following is a specification.

An object of the invention is to provide a 10 combined shelf and towel rack of a simple and durable construction and which is adapted not only for supporting the usual toilet articles but also for securing the towel in position to prevent the same from slipping 15 to the floor.

The invention embodies, among other features, a device that can be cheaply manufactured and which can be readily secured to a wall or to the back of a chair.

20 In the further disclosure of the invention reference is to be had to the accompanying drawings, constituting a part of this specification, in which similar characters of reference denote corresponding parts in all the 25 views, and in which:

Figure 1 is a perspective view showing the device in applied position, with a towel held in supporting position; Fig. 2 is a front elevation showing the towel bar in lowered position, with the towel removed; and Fig. 30 3 is a vertical transverse sectional view taken on the line 3—3 in Fig. 2.

Referring more particularly to the views, I disclose a combined shelf and towel rack 10 35 consisting of a shelf member 11 preferably formed of a single piece of stamped material, with the longitudinal edges 12 of the shelf member bent upwardly so that the shelf member 11 will have a channel shape, as 40 shown, ends 13 of the shelf member being bent downwardly to provide bearings on which a towel bar 14 is mounted to swing, the said towel bar being interposed between the ends 13 to lie beneath the shelf member 45 11. The rear upwardly bent edge 12 is preferably provided with apertures 15 through which suitable screws 16 are passed for the purpose of securing the shelf and towel rack 10 to a wall 17, it being understood that the 50 shelf and towel rack can also be conveniently secured to a chair or other article of furniture.

Struck from the body of the shelf member 11 are a plurality of ears 18 depending adjacent the front edge 12 and adapted to limit

the upward swinging movement of the towel bar 14, it being readily apparent by referring to the views that when the towel bar 14 is swung upwardly its medial straight portion will lie adjacent to and beneath the 60 front edge 12 of the shelf member, but in view of the manner in which the towel bar is arranged with respect to the shelf member, the said towel bar, when swung upwardly and not supporting a towel, will immediately 65 gravitate into lowered position. When a towel, however, is placed on the towel bar 14 and the same is swung upwardly, a portion of the towel will be interposed between the shelf member 11 and the straight portion 70 of the towel bar, so that this portion of the towel will frictionally engage the under side of the shelf member and bind relatively thereto, thus retaining the towel bar 14 in its uppermost position so that the towel will be 75 supported on the towel bar and be prevented from accidentally slipping to the floor, it being further apparent that portions of the towel will also lie between the towel bar and the depending ears 18. Therefore, from the 80 foregoing description it will be seen that when a towel is supported on the towel bar and prevented from slipping to the floor in the manner mentioned, and it is desired to remove the towel from the towel bar for use, 85 it is only necessary to pull downwardly on the edges of the towel, thus swinging the towel bar into lowered position so that the towel will be disengaged from the shelf member and can be readily removed from 90 the bar. Now when it is desired to return the towel to the bar 14 and secure the same in position to prevent the towel from slipping to the floor, it is only necessary to swing the towel over the towel bar so that 95 substantially the medial portion of the towel will be engaged by and lie upon the bar, and then the towel bar is swung upwardly so that the medial portion of the towel will engage the under side of the shelf member, 100 thus producing a binding effect which will hold the towel bar in its upper supporting position so as to bind the towel with respect to the shelf member and the towel rack and prevent the towel from accidentally slipping 105 to the floor.

It will be apparent that the device described can be very cheaply manufactured and preferably consists of only two parts, namely, a shelf member stamped or other- 110

wise struck from a single piece of material, and a towel bar which is arranged to swing on the shelf member.

Having thus described my invention, I 5 claim:

As a new article of manufacture, a towel 10 rack comprising a single piece of flat material having its ends bent downwardly to form bearings, a crank shaped towel bar mounted to swing on the bearings and normally depending beneath the flat portion of the said piece of material, with the said towel bar adapted to receive a towel and

movable upwardly to wedge the towel between the flat portion of the piece of material and the said towel bar, and ears struck downwardly from the piece of material and adapted to limit the swinging movement of the towel bar. 15

In testimony whereof I affix my signature 20 in presence of two witnesses.

FREDERICK W. KOEHLER.
